OPERATING UNIT FOR PHOTOGRAPHIC
COMPOSING APPARATUS AND THE LIKE

William C. Huebner, New York, N. Y.

Application May 25, 1944, Serial No. 537,236

10 Claims. (Cl. 95—4.5)

1

This invention relates to improved operating means or motors for the shutters and other elements of photographic composing apparatus of the nature disclosed in U. S. Patent #2,180,417, issued Nov. 21, 1939, to me, for Means for photographically composing type characters. Said patent discloses an apparatus comprising a font or set of printing or type characters including the lower and upper case letters, numerals, punctuation marks, signs, etc., necessary for use in composing printed or reading matter, such characters being disposed in a circular group or series; and optical projecting means including shutters operable for selectively or individually projecting images of the printing characters of such font for exposure in required relation on the sensitized or light sensitive surface of a film or other medium which is movable for receiving thereon in required positions, the successively projected character images.

The motors or operating means of this application are primarily intended to provide improved means for actuating the shutters of such apparatus to admit and shut off light for illuminating the printing characters, whereby the projecting lens or means of the apparatus project images of the characters individually or selectively to the sensitized surface.

One object of the invention is to provide a practical and efficient motor of improved, novel construction for operating a movable shutter or element of such apparatus.

Other objects of the invention are to provide a shutter operating system which is quick in action, simple in operation and designed to perform during the long periods of work needed to compose type photographically, and which, therefore, should be highly dependable in operation; also to provide means for quick and accurate control of character exposures in connection with the relay character selecting system and the character justification system disclosed respectively in my copending applications for U. S. patents, Serial Numbers 533,920 and 533,921, filed May 3, 1944; also to provide an electrically controlled pneumatic or fluid-pressure-operated motor unit which is of simple construction and of small, compact form, but is adapted to effect quick and positive substantial movements of an element by the simple operation of an electrical contact device or circuit closer; also to provide an electrically controlled, fluid-pressure-operated unit which is of a form adapting a large number of the units to be arranged closely together in a compact group or circular series suitable for op-

erating the shutters for the circular series of type characters of a photographic composing apparatus such as disclosed in said patent.

Further objects and advantages of the invention will appear from the following specification of the preferred embodiment of the invention shown in the accompanying drawings, and the novel features of the invention are set forth in the appended claims.

In said drawings:

Fig. 1 is a side elevation of a shutter-operating motor unit embodying my invention, showing in section, the supporting shutter board or portion of a photocomposing apparatus in which the unit is employed.

Fig. 2 is a bottom plan view of a portion of the plate having the printing characters, over which the motor units are mounted.

Fig. 3 is a central, longitudinal sectional elevation of the unit and its support, showing shutter closed.

Fig. 4 is a bottom plan view of the motor base.

Fig. 5 is a longitudinal, sectional elevation, similar to Fig. 3, of the unit, but showing the position of the parts when the shutter is open.

Fig. 6 is a fragmentary plan view of the motor base.

Fig. 7 is a face view showing a multiplicity of the motor units arranged side by side in circular series on the shutter board or supporting part of the photocomposing apparatus.

Fig. 8 is a transverse, sectional elevation thereof on line 8—8, Fig. 7.

The several operating motor units for the camera shutters are alike. Each unit comprises a slender, elongated body or casing 10 which is suitably secured, by screws 11 or otherwise, on a base plate 12 which is preferably of elongated, narrow and tapered form adapting a number of the units to be arranged radially side by side in a circular series and removably secured, as by screws 11a or otherwise, on a supporting shutter board or member 13. In a suitably shaped chamber or cavity 14 in the underface of the base plate 12, a shutter plate 15 is guided to slide lengthwise of the base, said shutter plate being adapted in one position of the shutter, shown in Fig. 5, to uncover openings 17 and 18 in the base plate 12 and shutter board, to permit the passage of light through said openings for illuminating one of the printing characters on an underlying character plate 19, and in another position of the shutter, shown in Fig. 3, to close said openings to shut off the light. The character plate 19 may be either an opaque plate with trans-

parent characters or a transparent plate with opaque characters.

20 indicates a piston, preferably in the form of a cylindrical rod, arranged to reciprocate in a bore or cylinder 21 extending lengthwise in the motor body 10 and connected to the shutter 15, as by a finger 22 projecting from the shank of the shutter plate into a hole in the piston, so that the shutter is reciprocated from its closed to its open position and vice versa by the reciprocation of the piston. As shown, the cylinder bore 21 extends through the motor body and is closed at opposite ends by screw plugs 21a having reduced inner ends forming stops to limit the opposite movements of the piston 20. In the motor body 10 is also provided a valve chamber 23, preferably in the form of a slender, cylindrical bore extending lengthwise through the motor body parallel with cylinder 21, and shiftable endwise in this chamber is a slender valve rod or element 24 which extends out of the valve chamber at the opposite ends of the motor body. By inward and outward or opposite movements of this valve rod 24, air or fluid under pressure is alternately admitted to and exhausted from cylinder 21 at opposite ends of the piston 20 for reciprocating the piston to open and close the shutter 15. The extent of the inward movement of the valve rod may be definitely fixed by engagement of a stop shoulder 24a on the valve rod with the adjacent end of the motor body 10.

The valve 24 is moved inwardly, or to the right, as illustrated, preferably by an electromagnet which, as shown, comprises two electrical coils 25 on a supporting frame 26 which is suitably mounted on top of the motor body 10, with the coils 25 extending one above the other lengthwise of the body. These coils and their supporting frame are preferably of a width approximately no greater than the width of the motor body so as not to project laterally beyond the sides of the body. The armature 27 of this magnet is pivoted at its upper or outer end portion to the magnet frame 26, with its opposite end portion arranged to engage the adjacent projecting end of the valve rod 24 for moving the latter inwardly when the magnet is energized and attracts the armature. A suitable spring 28 preferably in the form of a spring strip secured at one end to the motor body, at the end thereof opposite to that at which the magnet armature is located, and having its free end bearing against the adjacent projecting end of the valve rod, acts, when the magnet is deenergized or its operating current broken, to shift the valve rod in the opposite direction, or to the left, as shown in the drawings. This movement of the valve rod may be limited, as by engagement of a stop finger 28a on the magnet armature with the magnet frame 26.

In the position of the parts of the unit shown in Fig. 3 of the drawings, in which the shutter is closed, the magnet is deenergized and the spring 28 holds the valve rod in its initial or left-hand position. In this position, a reduced portion 29 of the valve rod admits pressure fluid from a fluid pressure supply chamber 30 on the motor body through ports or passages 31 and 32 in the motor body to the right hand end of cylinder 21. At the same time, a second reduced portion 33 of the valve rod permits the fluid to exhaust from the opposite end of cylinder 21, through ports or passages 34, 35 and 36 in the motor body to an exhaust port 37 leading to the atmosphere, whereby piston 20 is moved to the left, as shown in the drawings and closes the shutter and holds

it closed. When the parts are in this position, with the shutter closed, which is the normal position of the parts, if the control magnet 25 is energized, by closing its operating circuit, the magnet cores will attract the armature 27, which will shift the valve rod 24 in the opposite direction, against the action of spring 28, to the position shown in Fig. 5. In this position the reduced portion 29 of the valve rod will connect the passage 32 leading from the cylinder 21 with an exhaust port 38 to permit the pressure fluid to exhaust from this end of the cylinder and, at the same time, the reduced portion 33 of the valve rod will admit fluid from the pressure chamber 30 through ports 40, 41 and passages 35, 34 to the left hand end of cylinder 21, whereby the piston 20 will be moved to the right, as shown in the drawings, and will open the shutter. The piston will be retained in this position and hold the shutter open as long as the magnet circuit remains closed and the magnet energized, and when the circuit is broken to deenergize the magnet, the valve spring 28 will return valve rod 24 to its initial position, whereby the piston will be returned to its initial position and close the shutter, as shown in Fig. 3.

The magnet circuit can be controlled by the operation of any suitable circuit closer or contact device, and since the valve rod 24 is small and light and has only a relatively short stroke, it can be operated by a relatively small magnet. On the other hand, this control valve thus operated by an electrical relay device controls the flow of pressure fluid for operating the shutter operating piston 20 which can have the relatively much longer stroke required for moving the shutter to fully open and close a light opening of substantial area. Also, the pressure of the actuating fluid can be whatever may be necessary to insure quick, positive opening and closing movements of the shutter.

As shown in Fig. 7, a multiplicity of the electrically controlled motor units are arranged radially side by side in a circular series so that one unit is provided for the shutter for each of the several type characters of the photocomposing apparatus, and as shown in Figs. 5 and 7, the pressure chamber 30 for the supply of actuating pressure fluid to the several shutter-operating motors is formed by a continuous channel in a circular or annular ring or body 45 which extends over and is secured against the tops or outer faces of the bodies 10 of the several motors with the ring chamber 30 communicating with the supply ports 31 and 40 of each motor through which the pressure chamber 30 supplies fluid to the valve chamber 23. Fluid under pressure may be supplied to the pressure chamber 30, as by a supply pipe or line 46. In this way, pressure fluid from one supply source is delivered to the valve chambers of the whole series of motors, so that all of the motors may be operated by fluid under the same constant pressure, which pressure may be whatever is most appropriate, thus insuring uniform, positive action of all of the motors and shutters.

Only one of the type printing characters, as T, is shown in the drawing, see Fig. 2, in which the character is shown on the character plate 19 below the openings 17 and 18 in the overlying motor base and shutter board 13, but it will be understood, as explained in said Patent No. 2,180,417, that different printing characters are provided in a circular series on the character plate, one in register with the light holes 17 and

18 for each motor unit so as to be illuminated when its correlated shutter is opened by its operating motor.

It should be apparent, it is believed, that the shutter-operating motor units herein disclosed are adapted for use in apparatus for photographically composing type characters covered by the before mentioned Patent No. 2,180,417, in place of the shutter-operating solenoids or magnets shown in the patent, the magnets 25 of the units being controlled as explained in said patent, by finger keys, one of which operates a circuit closing switch for each magnet. However, as explained in said copending application, Ser. No. 533,920, the shutter-operating units are particularly desirable for use with the relay character-selecting system for photocomposing apparatus of said application, the magnets of the units being controlled automatically by the circuit closing means, disclosed in said application.

Furthermore, while the motor units of this application have been herein specifically described as operating means for the light shutters of photocomposing apparatus, they are also especially suitable for other purposes, as for instance, for operating the retracting and resetting devices for the stop elements of the variable step feed mechanism in the justification system of said other copending application, Serial No. 533,921.

I claim as my invention:

1. In a photographic composing apparatus having a series of characters, and correlated shutters controlling light for photographically producing images of said characters on a sensitized surface, the improved operating unit for each of said shutters comprising a fluid-pressure-actuated motor operatively connected to the shutter, and having a valve controlling the admission and exhaust of the actuating fluid for moving the movable member of said motor by fluid pressure alternately in opposite directions to open and close said shutter, and an electromagnetic device operable for shifting said valve to control the operation of said motor.

2. In a photographic composing apparatus having a plurality of characters arranged in a circular series, and correlated shutters controlling light for photographically producing images of said characters on a sensitized surface, the improved operating means for said shutters comprising fluid-pressure-actuated motors arranged in a circular series each radially with respect to one of said characters and operatively connected to the shutter correlated with said character, and having a valve controlling the admission and exhaust of the actuating fluid for moving the movable member of said motor by fluid pressure alternately in opposite directions to open and close said shutter, and an electromagnetic device operable for shifting said valve to control the operation of said motor.

3. In a photographic composing apparatus having a series of characters, and means correlated with said characters for producing images thereof in different positions on a sensitized surface, the improved operating unit for a movable element of said apparatus comprising a fluid-pressure-actuated motor with a movable member having a relatively long stroke operatively connected to said element, a valve with a movable member having a relatively short stroke controlling the admission and exhaust of the actuating fluid for producing alternate opposite movements of said movable motor member and movable element, and

an electro-magnetic device operable for shifting said valve to control the operation of said motor.

4. The improved shutter operating means for photographic composing apparatus according to claim 2, which includes an annular supply chamber for the motor actuating fluid connected by said valves with the several motors of said series.

5. In a photographic composing apparatus having a plurality of characters arranged in a circular series, and correlated shutters controlling light for photographically producing images of said characters on a sensitized surface, the improved operating means for said shutters comprising fluid-pressure-actuated motor units arranged in a circular series each radially with respect to one of said characters, each of said units comprising a radially elongated narrow motor body with a guide in which the correlated shutter is movable lengthwise of said body, a piston which is operatively connected to said shutter and is movable lengthwise in said body, a valve controlling the admission and exhaust of the actuating fluid for operating said motor to open and close said shutter, and an elongated narrow electromagnetic device mounted on said motor body lengthwise thereof and operable for shifting said valve to control the operation of said motor.

6. The improved shutter operating means for photographic composing apparatus according to claim 5, in which said motor units carrying said shutters are individually removably mounted in said apparatus.

7. In a photographic composing apparatus having a series of characters, and correlated elements operable for producing images of said characters on a sensitized surface, the improved operating means for said elements comprising elongated fluid-pressure-actuated motor units arranged in a series lengthwise radially relatively to each other and each lengthwise of the direction of movement of the element actuated thereby, each of said units comprising a radially elongated narrow motor body and a piston, one of which parts is movable in the direction of the length of the body and is operatively connected to the correlated element, a valve controlling the actuating fluid for reciprocating said movable motor part and element, and an elongated narrow electromagnetic device arranged lengthwise of said motor body and operable for shifting said valve to control the operation of said motor.

8. In a photographic composing apparatus having a circular series of characters, and correlated elements operable for producing images of said characters on a sensitized surface, the improved operating means for said elements comprising fluid-pressure-actuated motor units arranged in a circular series each radially with respect to one of said characters, each of said units comprising a radially elongated narrow motor body with a guide in which the correlated element is movable lengthwise of said body, a piston which is operatively connected to said element and is movable lengthwise in said body, a valve controlling the admission and exhaust of the actuating fluid for reciprocating said piston and connected element, and an elongated narrow electromagnetic device arranged lengthwise of said motor body for actuating said valve to control the operation of said motor.

9. In a photographic composing apparatus having a series of characters, and correlated shutters controlling light for photographically producing images of said characters on a sensitized surface, the improved shutter-operating and mounting

unit, comprising a relatively long narrow motor base movably supporting said shutter, a relatively long narrow, fluid-pressure-actuated motor arranged lengthwise on said base and having a member movable in the direction of the length of said base and operatively connected to said shutter, a valve controlling the actuating fluid for reciprocating said movable motor member and shutter, and an elongated narrow electromagnetic device arranged lengthwise of said motor body 10

and operable for shifting said valve to control the operation of said motor.

10. The improved shutter operating means for photographic composing apparatus according to claim 5, which includes an annular supply chamber for the motor actuating fluid extending about the center of said circular series of motor units and communicating through said valves with the several motors.

WILLIAM C. HUEBNER.
